MEANS FOR PREVENTING PREMATURE
FIRING OF DEPTH CHARGES

John L. Andrews, Fairfield, Ill.

Application February 13, 1946, Serial No. 647,415

5 Claims. (Cl. 102—7)

(Granted under the act of March 3, 1883, as
amended April 30, 1928; 370 O. G. 757)

1

This invention relates generally to a depth charge and more particularly to new and improved means for preventing firing thereof in response to shocks such as are received, for example, by the depth charge upon impact with the water during the launching operation thereof.

In certain types of depth charges heretofore employed in service and having, among other elements, certain elements adapted to be moved relative to each other in response to the pressure of the surrounding water to fire the depth charge, it has been discovered that in certain positions of the depth charge at the moment of impact sufficient inertia forces may be developed which cause these parts to move to their firing positions, thereby to fire the depth charge prematurely.

In the device of the present invention this difficulty has been overcome by employing a toggle arrangement having a pair of inertial elements secured thereto for restraining the movement of the hydrostatic element to the firing position until the deceleration of the depth charge has subsided during movement of the depth charge through the water. In accordance with the preferred form of the invention, this is accomplished by employing the inertial forces set up within the inertial members at the moment of impact of the depth charge with the surface of the water to prevent premature movement of the toggle joint and the hydrostatic element to the firing position as the result of the aforesaid impact or as the result of a shock received through the surrounding water caused by the explosion of another depth charge or the like within the vicinity of the device.

An object of the present invention is to provide new and improved means for generating inertial forces adapted to prevent the inertial forces of the firing parts from causing movement thereof upon impact of the depth charge with the water.

Another object is to provide inertial means for locking the firing elements of the depth charge against movement upon impact of the depth charge with the water without interfering with the normal operation of these parts in response to an increase in the hydrostatic pressure of the surrounding water.

Another object is to provide a depth charge having an inertial controlled toggle linkage for preventing firing thereof in response to shocks received thereby in which means are provided for reducing the inertial forces set up within the inertial elements at the moment of impact of the depth charge with the surface of the water.

A further object is to provide new and improved means for preventing firing of a depth charge in response to shocks received thereby which employs a minimum number of parts.

Still other objects, features and advantages of the present invention are those relating to the

2

novel construction combination and arrangement of parts as will best be understood from the following description of a preferred embodiment of the invention, reference being had to the accompanying drawings wherein:

Fig. 1 is a view in elevation and partly in section of a depth charge pistol employing the inertial locking means of the present invention according to the preferred embodiment thereof;

Fig. 2 is a view of the depth charge pistol taken substantially along the line 2—2 of Fig. 1;

Fig. 3 is a sectional view partly broken away along the line 3—3 of Fig. 1;

Fig. 4 is a view similar to Fig. 1 and illustrating the inertial locking means in the unlocked position thereof; and

Figs. 5, 6 and 7 are detail views of one of the weights comprising the inertia locking means.

In the accompanying drawings, the numeral 10 generally designates a depth charge pistol suitable for use with a depth charge of a type such as that disclosed and claimed in the copending application of Harry H. Moore et al. for Depth Charge Firing Mechanism, Serial No. 474,354, filed February 1, 1943. The pistol disclosed in the present application, except for the inertia locking means hereinafter to be described, is substantially the same as that disclosed in the copending application and reference may be had thereto for details of construction and operation.

It will suffice for purposes herein, therefore, to briefly point out that the pistol comprises a cylindrical casing 11 to which one end, not shown, of a bellows 12 is secured and sealed in watertight relation therewith, the other end of the bellows 13 being movable to drive a cup-shaped member 13 as the bellows is expanded under pressure of the surrounding water admitted thereto by way of ports and apertures, not shown.

40 Cup-shaped member 13 has mounted thereon a supporting block assembly 14 for a plurality of leaf springs 15, one of which carries on the end thereof a firing pin 16. As the cup-shaped member is driven progressively by the bellows as the depth charge descends through the water, the firing pin is moved along the inclined portion 17 of a cam 18 until the pin passes beyond the upper end of the cam, thereby causing the pin to strike a percussion cap 19 to ignite an explosive train and booster charge which in turn fires the main explosive charge of the depth charge.

A booster charge is contained within the cylinder 21 which is held in fixed space relation with flange 23 by the spacing collars and screws 55 20, the tubular member 22 being interposed therebetween. Flange 23 is fitted into fixed registered engagement with the tubular casing 11 as at 24. The flange 23 also supports a cylindrical member 25 which is telescopically fitted within member 13 and having a portion of the explosive

train arranged therein and through which the percussion cap operates to ignite the explosive train, the percussion cap 19 and cam 18 adjacent thereto both being supported by and secured to the member 25.

A piston 26 is telescopically fitted within cylindrical member 25 and carries axially thereof an electroresponsive detonator 27, Fig. 3, which is electrically connected to terminals 28 forming a part of a magnetic influence system adapted to fire the detonator when the depth charge moves within the vicinity of a submarine. The piston is adapted to be moved by the bellows such that the detonator is moved into operative relation with the explosive train during descent of the depth charge but prior to movement of the firing pin into its firing position, whereby the depth charge may be fired by the influence means prior to self-destruction thereof which is accomplished at a predetermined depth of submergence by the hydrostatically controlled percussion means.

Key and slot means 29 and 31 are employed to prevent relative rotation between piston 26 and member 25, and, similarly, a slot 32 is formed in member 25 to receive the tip of a shoulder screw 33 to prevent relative rotation between cup-member 13 and member 25 whereby the angular orientation of the detonator with respect to the explosion train is not disturbed during movement of the piston.

The inertia locking means for preventing movement of the firing pin in response to shocks received by the depth charge during launching thereof or from other causes such as result from the inadvertent or accidental dropping thereof or from countermine shocks will now be described.

The locking means comprises a toggle system of levers for interconnecting the cup member 13 and flange 23 and a plurality of inertia responsive members carried by the levers in such a manner as to cause the lever system to effect a restraining action between the cup member 13 and flange 23 whereby shocks received by the depth charge are ineffective to actuate the hydrostatic element to the firing position regardless of the direction from which the shocks are received. Under normal conditions, however, the cup-member is free to drive the levers and inertia members so as to produce movement of the firing pin to fire the depth charge, as heretofore described. Yieldable means comprising a pair of springs is employed with the lever system to prevent damage to the pistol by reason of inertia forces developed by the inertia members when shocks are received in a direction to set up forces tending to drive the cup-member in an opposite direction from its normal firing movement.

The lever system includes a T-shaped member 34 which is secured to cup-member 13 as by the shoulder screw 33. A pair of lever arms 35 and 36 are pivotally secured to the T-member 34 as at 37 and 38 respectively. Arms 35 and 36, in turn, have pivotally secured thereto as at 39 and 40 a pair of levers 42 and 43 respectively. These levers, in turn, are pivotally secured as at 44 and 45 within a slotted member 46 having apertured ears 47 and 48 through which shoulder screws 49 and 51 slidably pass. These screws are securely tightened into a C-shaped member 52 which is secured to flange member 23 as by bolts 53. A pair of springs 54 are coiled about screws 49 and 50 respectively so as to normally yieldably urge the slotted member into substantially abutting relation with C-shaped member 52.

The springs 54 assure that the levers 35, 36 and 42, 43 approach the dead center condition so that the levers 42 and 43 are in contact with and limited by surfaces 57. This insures that the linkage initially will be in the proper position to make maximum use of inertia even though dimensional variations exist in the mechanism. The springs 54 also permit the use of wide commercial tolerances without impairing the operation of the mechanism.

The levers 35 and 36 have attached thereto, or made integrally therewith, the weights 55 and 56 so mounted and arranged thereon as to prevent alignment of the center lines of the levers as used in combination with the levers 42 and 43. This is accomplished by mounting each of the weights such that surface 57 thereof forms an angle with the center line extending through the pivots of the lever affixed thereto whereby the extending portion 58 of each weight engages the lever 42 or 43 cooperating with the lever arms 35 or 36 respectively before the center lines of these levers move into alignment, as best seen in Fig. 1. Thus, a dead center condition of the lever system is avoided whereby the system may be actuated by the cup member 13 to move the weights outwardly, as best seen in Fig. 4, as the cup member is moved from its position as seen in Fig. 1 by the hydrostatic pressure acting thereon.

In the event that shocks are received by the depth charge in such a direction as to tend to move the cup member 13 and firing pin 16 carried thereby toward its firing position, inertia forces also act upon weights 55 and 56, which forces tend to move the weights inwardly, thereby to lock the lever system and prevent movement of cup member 13. Shocks received by the cup-shaped member 13 and parts secured thereto tending to move the cup member in the opposite direction also tend to move the weights outwardly. If the member 47 were rigidly secured to C-shaped member 52, these shocks might produce stresses in the lever system, particularly at shoulder screws 49 and 51, sufficient to rupture or otherwise damage the lever system. This condition is avoided by the yieldable mounting between slotted member 46 and C-shaped member 52, which yieldable mounting is adapted to absorb such shock effects sufficiently to prevent damage to the lever system and mountings therefor.

The weights 55 and 56 may be so proportioned as to fit into any suitable type depth charge pistol. In the pistol 10 disclosed herein, for example, the inner surface 59 of each weight is formed to fit about the cylindrical member 25, inner surface 60 is curved so as to clear cup member 13 when the lever system is fully actuated, and the outer surface 61 thereof is curved in such a manner as to fit inside the casing 14 and allow movement of the lever system without mechanical interference.

While the invention has been described with particularity as to a specific example thereof comprising a plurality of weights and levers adapted to fulfill the aforesigned objects of the invention, it will be understood that this has been done for purposes of disclosure and that various changes and substitutions will be readily apparent to those skilled in the art, after understanding the invention, and that the terms employed in the claims are to be considered as words of description rather than of limitation.

The invention herein described and claimed

may be manufactured and used by or for the Government of the United States of America for governmental purposes without payment of any royalties thereon or therefor.

What is claimed as new and desired to be secured by Letters Patent of the United States is:

1. In a depth charge of the character disclosed, the combination of a support, means including a firing member adapted to be moved within said support to a firing position under pressure of the surrounding water thereby to fire the depth charge, a toggle linkage including pairs of mutually connected links, one end of each of said pairs of links being connected to said member and the other end of each of said pairs being connected to said support and adapted to be flexed by the member as the member moves to the firing position, and a plurality of inertia devices carried by said toggle linkage, one of said inertia devices being attached to one of the links of each pair of links and responsive to shocks received by the depth charge to resist flexing of the linkage for preventing movement of the firing member to said firing position in response to said shocks, said inertia devices engaging the other ones of said pairs of links to prevent locking of said links on dead center.

2. In a depth charge of the character disclosed, the combination of a depth charge pistol having a supporting structure and a firing member adapted to be moved relatively thereto under pressure of the surrounding water into a predetermined firing position thereby to fire the depth charge, a lever pivotally secured at one end thereof to said member, a second lever pivotally secured at one end thereof to said first named lever and at the other end to said supporting structure, said levers being arranged such that their pivotal centers are slightly out of alignment when the firing member is in an initial unmoved position whereby said levers are free to move further out of alignment as said firing member moves to said firing position, and an inertia device carried by one of said levers and arranged thereon, said inertia device being adapted to engage the other of said levers thereby to prevent the levers from being moved into a position such that their pivotal centers are in dead center alignment, said inertia device being urged into said engagement with the other of the levers in response to a shock force which urges the firing member toward the firing position thereby to prevent movement of the member thereto in response to said shock force.

3. In a depth charge of the character disclosed, the combination of a depth charge pistol having a supporting structure and a firing member adapted to be moved with respect thereto under pressure of the surrounding water from an initial position into a predetermined firing position thereby to fire the depth charge, a pair of toggle joints comprising a pair of levers for preventing movement of the firing member to said firing position in response to a shock received by the depth charge, each of said levers being secured at one end thereof to said member, and a second pair of levers, each of said second levers being pivotally secured at one end thereof to a lever of said first named pair of levers respectively, a movable support pivotally secured to the other end of each of said second levers, means of yieldably securing said movable support to said supporting structure thereby to prevent damage to said levers and the firing member

connected thereto as a shock is received by the depth charge, the levers of each of said toggle joints being arranged such that their pivotal centers are substantially in alignment when the firing member is in said initial position, and a pair of inertia devices respectively carried by one of said pairs of levers and movable therewith, said inertia devices being adapted to engage the levers of the other pair respectively when the firing member is in said initial position thereby to prevent the levers of each of said toggle joints from being moved into alignment.

4. In a depth charge of the character disclosed, the combination of a depth charge pistol having a supporting structure and a firing member adapted to be moved relatively thereto under pressure of the surrounding water into a predetermined firing position thereby to fire the depth charge, a lever pivotally secured at one end thereof to said member, a second lever pivotally secured at one end thereof to said first named lever and at the other end to a supporting member, a yieldable connection between said supporting member and said supporting structure, said levers being arranged such that their pivotal centers are substantially in alignment when the firing member is in an initial unmoved position, and an inertia device carried by one of said levers and arranged thereon, said inertia device being adapted to engage the other of said levers thereby to prevent the levers from being moved into a position such that their pivotal centers are in dead center alignment.

5. In a depth charge of the character disclosed, the combination of a depth charge pistol having a supporting structure and a firing member adapted to be moved relatively thereto under pressure of the surrounding water into a predetermined firing position thereby to fire the depth charge, a lever pivotally secured at one end thereof to said member, a second lever pivotally secured at one end thereof to said first named lever and at the other end to a supporting member, a yieldable connection between said supporting member and said supporting structure, said levers having the pivotal centers thereof slightly out of alignment when the firing member is in an initial unmoved position and flexed well out of alignment when in the firing position, and an inertia device carried by one of said levers for maintaining the levers against flexing when inertial force is applied to the firing member thereby to prevent movement of the firing member to the firing position, said inertia device engaging the other of said levers while in the initial unmoved position to prevent movement of the levers into a position such that the pivotal centers thereof are in dead center alignment.
